FIG - 4

HEAT REGENERATOR, PARTICULARLY A HOT BLAST STOVE FOR A BLAST FURNACE PLANT

This invention relates to a heat regenerator, in particular to a hot blast stove for a blast furnace plant, comprising a vertical structure of masonry, closed at the top by a dome of refractory bricks.

In particular in the blast furnace art there is an ever increasing need of air preheaters, so-called hot blast stoves, sufficing higher requirements of operation. As the blast furnaces are in these days increasing in dimensions and capacity and have to produce pig iron at a higher efficiency, the hot blast stoves for such blast furnaces have to supply ever increasing quantities of air at higher temperatures. This entrains that the refractory domes of such stoves also have to have larger dimensions and that these domes and the structure of the connection thereof to the remainder of the stove have to be able to withstand higher temperatures.

In this respect it may be remarked that the domes should be able to withstand temperatures up to about 1800° C during operation, and also have to withstand considerable temperature variations in short time intervals during heating up and cooling down.

It has appeared that the large and non-uniformly distributed thermal dilatations of the dome cause considerable difficulties, particularly in the zone of the connection between the dome and the remainder of the structure. The differences in dimensions occurring between the lower edges of the dome and the upper edge of the vertical masonry structure of the stove below the dome may amount to about 1 percent of the dimensions of this part of the stove. This gives rise to the formation of serious vertically extending cracks or fissures in the dome.

Although as a rule such cracks were already known for smaller air preheaters, heated to lower temperatures, they did not cause serious problems in such smaller stoves. For larger brick domes, however, where 40 stability is already an important problem without such effects, the occurrence of cracks will more easily have fatal results.

Particularly if the temperature of the dome will rise up to about 1600° C, the danger of collapse of the 45 dome will become very great.

The above is true both for domes of hot blast stoves with an internal burner stack as for stoves with an external burner stack.

In view of the above the invention aims at providing such a structure of the dome of such stoves that such cracks cannot or can hardly occur and even if they occur, will not do harm. In view thereof a structure according to the invention as given above is characterized in that the dome passes into the vertical masonry structure below it by means of a continuous series of elements which are pivotally connected both to the stove structure below it close to the upper edge of the vertical masonry structure and to the lower edge of the dome.

Where in this specification reference is made to structures in which the dome passes into the vertical masonry structure, structures are also deemed included in which this connection is not realized in contact with the upper edge of the vertical masonry of the stove itself below the dome, but in contact with an annular element provided all around this upper edge for giving a

support of the dome not upon but outside the vertical masonry structure below the dome.

Preferably according to the invention the said pivoting elements have the shape of columns being more or less in line with the adjacent part of the dome for each column, the pivots being formed by supporting surfaces having the shape of faces being parts of circular cylinders on the one hand at the upper ends of the columns and the lower edge of the dome and on the other hand at the upper edge of the vertical masonry structure.

It is remarked that such a possibility of movement of the columns by pivoting at both ends has clear and considerable advantages over a support of the dome on balls or on rollers at the upper edge of the vertical masonry structure.

In this respect it is remarked that such pivotable columns, also by their greater length, can take up considerable differences in dilatation much more easily than rollers. More important, however, is that the rollers should be cooled locally in order to avoid their being sintered to one mass with the surrounding brick structures. Moreover, as a result of such cooling of the rollers, the adjacent part of the dome will become too cold. This would again cause serious cracks in the dome as a result of the discontinuity in the dilatation characteristics of the refractory material of the dome in the temperature region at which this dome would have to operate.

As the dome according to the invention will have obtained a free possibility of movement with respect to the remainder of the structure and also as the dome is allowed to obtain a substantially constant temperature, it is thereby made possible to build up this dome entirely from silicon bricks.

In other structure it has appeared that the unavoidable considerable differences in temperature of the dome make it impossible to choose this material, which for other reasons is preferable. This would be due to the fact that there are considerably great and sudden temperature dilatations occurring in silicon bricks when passing their recrystallization temperature.

It has appeared that it is possible for the columns to take up the same temperature as the dome without any harm. Even if this would cause some slight sintering in the pivoting connections, this is easily loosened again in practice without any harm to the structure. This is a result of the bending moment which is exerted on the pivots and which by the larger lever arms of such moments is much greater than the bending moment which would occur in rollers as indicated above.

It is remarked that in general in refractory structures, and in hot blast stoves in particular, there is the general tendency to decrease thermal stresses by applying a more heavy and more rigid structure. The many uncertainties which occur in refractory structures which are highly loaded mechanically, particularly during heating up and cooling periods, are a ground for the fact that the experts did usually not dare to build less heavy and less rigid structures with more freedom of movement. Thus the structure according to the invention with a dome supported all around through many pivots is a structure which is not at all obvious for the expert, which is of a daring nature technically and which is quite surprising in its effects.

In order to restrict to a minimum a free movability of the dome on the remainder of the structure other than for taking up differences in thermal expansion it is according to the invention preferable to give the columns in the direction of their mutual row or series (so in the peripheral direction of the stove) a dimension which for each of them is 1 to 2 times larger than the dimension of the columns in their thickness direction (about radially of the stove). Thereby each column is substantially only allowed to rotate about one axis and it is thus restricted in its possibilities of movement by all other columns being pivotable about axes having different directions. This avoids the dome to move around its own axis.

It is known as such, e.g., for steel bridges, to use very short pivoting columns at the supports thereof. However, such supports only serve to take up displacements in one direction and of much smaller size. Moreover, such columns are in those cases as a rule formed as parts of rollers, so that the possibility of movement is in fact only a rolling movement and no pivoting movement.

In further contradistinction to this known structure it is according to the invention preferable to provide the pivots at both ends of the columns with convex upper surfaces, cooperating with concave lower surfaces.

Although this structure is not very obvious, it has the advantage that the columns, which are relatively long with respect to the dimensions of the pivots, have less possibility to pivot out of the space between the dome and the remainder of the structure.

In order to make the movement of the columns better predictable, but also for other reasons of a nature important in the building of furnaces, care should be taken that the columns at their lower ends can only move as slightly as possible in a radially outer and inner direction. This also avoids that the slots between the columns would become too wide.

This object is according to the invention obtainable if the upper end of the vertical masonry structure below the dome is provided at least in part with vertically extending expansion joints, said upper end being backed up by means which leave the shape thereof substantially unaltered with considerable varying temperatures of the vertical masonry structure. Such means could, e.g., have the shape of an annular element around the upper edge of the vertical masonry structure, such an annular element being known as such, the dome passing into said annular element through the columns. The means for backing up the said upper end as a rule consist of an obvious steel structure, provided in a region where the temperature is always sufficiently low.

It has already been remarked that the structure according to the invention could be applied for air pre-heaters such as hot blast stoves both with interior and also with exterior burner stack. When applying the invention to an interior burner stack structure it appears to be advantageous to take into account the manner of supporting the dome according to the invention in choosing the shape of the dome.

In this respect it has appeared that in such a new structure through which the side wall of the stove passes into the dome for a hot blast stove with a main body being a circular cylinder and with an interior burner stack, this dome should preferably have the

shape of a segment of a sphere which in a section along a meridian covers an arc of 100° to 110° , this segment of a sphere merging into a surface of revolution which in a meridian section consists of two circular arcs (one on each side) which have a radius which is 3 to 4 times larger than the radius of the segment of a sphere.

The invention will now further be explained with reference to the enclosed drawings giving by way of example only a preferred embodiment of the invention.

FIG. 1 gives a diagrammatic vertical section through a hot blast stove according to the invention;
FIG. 2 gives detail II in FIG. 1 on a larger scale;
FIG. 3 gives detail III of FIG. 1 on a larger scale;
FIG. 4 gives the same detail as detail II of FIG. 1 (FIG. 2), but of a different embodiment.

In FIG. 1 reference numeral 1 indicates a vertical cylindrical refractory brick wall of a hot blast stove. This stove as shown has an interior burner stack 2, which is separated from the space 4 by a separating wall 3. In space 4 there is a pile of refractory bricks adapted to take up heat from hot gases and to give off heat to air to be preheated and such a pile of bricks is not shown but is quite usual and known as such.

At the upper end the structure is closed by dome 5 of refractory material symmetrical to a vertical central axis. Around this structure there is a steel jacket as is usual, which is not shown.

A supply duct for air 6 and a supply duct for combustible gas 7 open into a burner 8 as usual. A grid 9 supports the said pile of bricks in space 4. There is an opening 10 below this grid for allowing gases to escape after giving off their heat to the pile of bricks and for cold air to enter the stove for being heated. An opening 11 in wall 1 in the burner stack allows the heated air to leave the preheater.

The dome consists of a part 12 having the shape of a segment of sphere, passing into the dome part 13 which is part of a surface of revolution. The radius of the spherical part 12 is about 35 percent of the diameter of the outer wall 1 and in a section through a meridian covers an arc of 104° . The dome part 13 merges without a sharp transition into part 12 and in a meridian section part 13 has a radius which is about 3.7 times the radius of segment 12. The transition zone of dome part 12 into dome part 13 has been shown by a dotted line in FIGS. 1 and 2.

With the aid of columns 14 the dome 5 is supported 50 pivotally on the outer wall 1. However, it is also possible to support the dome on an annular element not shown, which is connected to the surrounding steel jacket around the outside of the upper edge of outer wall 1, e.g., in a manner which is known as such.

In FIGS. 2 and 3 this support has been shown in more detail, FIG. 2 showing the support in a vertical section according to detail II in FIG. 1 and according to the line II-II in FIG. 3.

FIG. 3 shows detail III of FIG. 1 in a view from the interior radially outwards.

The lower edge of dome part 13 is rounded according to a semi-circular shape. The semi-cylinder thus formed fits into semi-cylindrical concavities in the upper ends of columns 14. To obtain such straight parts it is possible to have the bricks in the lower part of the dome part 13 follow such a configuration that this lower edge only consists of a number of straight parts.

In a similar manner the semi-circularly rounded lower edges of the columns 14 fit into semi-cylindrical concavities in the top edge of the vertical brick wall 1 of the stove.

The top part of the vertical masonry structure of wall 1 is provided with vertical expansion joints or slots 17, closing when the stove reaches the operating temperature, or at least closing partly, serving to avoid high compression stresses in the bricks and high tensile stresses in the steel outer lining when the stove is at 10 operating temperature.

The columns 14 have the same thickness as dome part 13, e.g., somewhat more than 30 cm.

The width of the columns 14 is preferably about 60 cm.

In FIG. 4 detail II of FIG. 1 is shown for a different embodiment, in which the dome is not directly supported by the vertical masonry of the stove. A steel shell 18 surrounds this masonry and merges upwardly into an annular part 23 flaring outwardly and merging itself upwardly into the steel outer structure of the dome. Annular part 23 is supported by a row of steel brackets or struts 24 around the outside of the stove.

The vertical masonry of the stove in the top part is here shown to consist of three layers 19, 20 and 21, having vertical dilatation joints 17 in planes through the axis of the regenerator similar to those in FIGS. 2 and 3.

The annular part 23 with brackets 24 are positioned in a relatively cool area, so that they do not expand considerably when the stove is heated. Thus also the diameter of the vertical masonry 19, 20 and 21 remains substantially unaltered. The expansion of this masonry by heating is thus almost entirely taken up by the joints 17 dimensioned so as to be entirely closed in operating conditions of the highest temperature.

The annular part 23 supports pivoting blocks 25, into which columns 26 fit in a pivoting manner. These refractory columns are essentially of the same shape and kind of material as the columns 14 in the previous embodiment. They support the dome by pivoting connection with the lower edge of the inner dome 27 of refractory bricks. Outside this dome 27 a second refractory brick layer 28 is present, in contact with the 45 steel outer lining of the dome.

The vertical masonry wall could, instead thereof, be flared outwardly to overly the annular part 23, in which case the pivoting blocks 25 will be positioned on top of this part of the vertical masonry wall of the regenerator. Many details of the regenerator, which are not important for understanding the invention, have not been shown and described. So, it will be clear that there is a steel dome over the refractory dome 5 and a porous, somewhat elastic heat-insulating layer between these 55

domes, as is usual. Such details will be clear to the expert.

What we claim is:

1. A heat regenerator, in particular a hot blast stove for a blast furnace plant, comprising an upstanding masonry structure, closed on top by a dome of refractory bricks,

characterized in that the dome passes into the vertical masonry structure below it by means of a continuous series of elements which are pivotally connected both to the stove structures below it close to the upper edge of the vertical masonry structure and to the lower edge of the dome.

2. A heat regenerator according to claim 1,

characterized in that the said pivoting elements have the shape of columns being more or less in line with the adjacent part of the dome for each column, the pivots being formed by supporting surfaces having the shape of faces being parts of circular cylinders on the one hand at the upper ends of the columns and the lower edge of the dome and on the other hand at the upper edge of the vertical masonry structure or other structure below such columns.

3. A heat regenerator according to claim 2,

characterized in that the columns in the direction of their mutual row or series (so in the peripheral direction of the stove) have a dimension which for each of them is 1 to 2 times larger than the dimension of the columns in their thickness direction (about radially of the stove).

4. A heat regenerator according to claim 2,

characterized in that the pivots at both ends of the columns have convex upper surfaces cooperating with concave lower surfaces.

5. A heat regenerator according to claim 1,

characterized in that the upper end of the vertical masonry structure below the dome is provided at least in part with vertically extending expansion joints, said upper end being backed up by means which leave the shape thereof substantially unaltered with considerably varying temperatures of the vertical masonry structure.

6. A heat regenerator according to claim 1, having the shape of a cylindrical hot blast stove with a circular cross-section and interior burner stack,

characterized in that the top part of the dome has the shape of a segment of a sphere which in a section along a meridian covers an arc of 100° to 110°, this segment of a sphere merging into a surface of revolution which in a meridian section consists of two circular arcs (one on each side) which have a radius which is 3 to 4 times larger than the radius of the segment of a sphere.
